FIG.1

FIG.2

FIG.3

FIG.4

FIG. 1 is a top plan view of an expansible link chain for a bracelet or similar article embodying my new design with the links in contracted position;

FIG. 2 is a view similar to FIG. 1 with the links in an expanded position, portions of the conventional appearing bottom links being visible between the expanded top links;

FIG. 3 is an enlarged top plan view of a single top link of the expansible chain; and

FIG. 4 is an enlarged perspective view of the top link shown in FIG. 3.

The stippled central portion of the upper surface of each link has a dull satin finish and the upper surface of the end portion of each link has a polished finish.

I claim:

The ornamental design for an expansible link chain for a bracelet or similar article, substantially as shown and described.
